DRILLING HOOK

Herbert E. Grau and Richard K. Hertel, Vernon,
Calif., assignors to Byron Jackson Co., Hunt-
ington Park, Calif., a corporation of Delaware

Application December 6, 1937, Serial No. 178,240

19 Claims. (Cl. 294—82)

This invention relates to hoist line hooks, such as are used particularly in the drilling of oil wells. More specifically, the invention relates to the general type of hook disclosed in the patent to N. K. Smith, No. 1,825,018, issued September 29, 1931, and involves various modifications and improvements of the hook construction disclosed in that patent.

A broad object of the invention is to provide a drilling hook having a hook portion and a hook-supporting portion pivotally connected thereto for free rotation about a vertical axis and also having a universal connection for permitting free swiveling of the hook relative to the hook-support in any horizontal direction.

Another object is to provide a drilling hook having a hook portion and a hook-supporting portion with a swivel connection therebetween, and means for locking the swivel connection against swivel movement.

Another object is to provide a drilling hook having a hook portion and a hook-supporting portion swivelly connected thereto with a simple and effective brake mechanism for limiting the freedom of swivel movement.

Another object is to provide a drilling hook having a hook portion, a hook-supporting portion, and a swivel mechanism interconnecting the two in which the swivel mechanism is well protected from contact with dirt and debris.

Various other objects, together with the specific features and advantages of the invention, will become apparent from the following description of a preferred form thereof, with reference to the drawings.

In the drawings:

Fig. 1 is a side elevation of a drilling hook in accordance with the invention.

Fig. 2 is a front elevation of the drilling hook.

Fig. 3 is a vertical section, taken approximately in the plane III—III of Fig. 2.

Fig. 3a is an enlarged detail section taken in the same plane as Fig. 3, to better bring out certain details of construction.

Fig. 4 is a cross section, taken in the plane IV—IV of Fig. 3.

Fig. 5 is a detail vertical section taken approximately in the plane V—V of Fig. 1.

Fig. 6 is a detail cross section, approximately in the plane VI—VI of Fig. 3a.

Fig. 7 is a detail vertical section similar to Fig. 3a, but taken in the plane VII—VII of Fig. 6.

Referring to Fig. 1 of the drawings, our hook comprises as its essential elements a bail 1 in the form of an inverted U-shaped member adapt-

ed to be detachably connected to a traveling block or other housing device, not shown, and having its two ends connected to the upper end of a housing 4. The housing 4 contains a spring mechanism for supporting a hook body 33, having at its lower end a bill 10 which constitutes the hook proper.

Referring now to Figs. 1 and 3, the lower ends of the bail 1 are provided with eyes 2 through which extend pins 3 for securing the bail to the housing 4, the latter having a pair of oppositely disposed laterally extending slotted ears 8 (Fig. 2) through which the pins 3 extend.

The housing 4 is approximately cylindrical in shape, except for the protruding ears 8, and is open at both its upper and lower ends. The upper end of the housing 4 is closed with a removable cover 5 secured in position by nut 7 (Fig. 2).

Positioned within, and extending up through the housing 4 is a hook shank 15 (Fig. 3), which hook shank functions to support the hook body 33 from the housing 4. The connection of the lower end of the shank 15 to the body 33 will be described in detail later. Suffice it to say that the lower end of the shank 15 passes through an aperture defined by an annular inwardly extending flange 14 on the lower end of the housing 4, which flange 14 makes a close sliding fit with the hook shank 15 for free vertical movement of the shank 15 downwardly with respect to the housing 4. Upward movement of the shank 15, with respect to the housing 4 from the position shown in Fig. 3, is limited by an outwardly extending annular flange 27 on the shank 15 which normally bears against the underside of the flange 14.

The shank 15 is resiliently supported against downward movement with respect to the housing 4 by a pair of helical springs 18 and 19, respectively, which are compressed between a nut 10 on the upper end of shank 15 and the lower end of the housing 4. Thus the lower end of the inner spring 18 rests against the upper face 17 of the flange 14 and the lower end of the outer spring 19 is supported on the upper face of an inwardly extending annular flange 20 on the housing 4, which flange 20 is of larger internal diameter and is positioned slightly above the flange 14.

The nut 10 is screwed onto the upper end of the shank 15, as previously indicated, and the normal compression of the spring members 18 and 19 may be adjusted by turning the nut 10 on shank 15. It is necessary, however, to firmly lock

the nut against rotation after it has once been set. There are several ways in which the nut can be locked; the particular, effective method is shown in Figs. 3 and 4, in which the extreme upper end of the shank 15, above the threaded portion thereof, is made polygonal in shape, thereby providing a plurality of flat surfaces 22, one of which is adapted to bear against a flat side of a wedge-shaped key 21, which key is received in a slot 25 formed in the upper end of a nut 18. One end of the slot 25 is closed by a web 28 (Fig. 4) having a hole therein through which extends a bolt 24. The wedge-key 21 is provided with a threaded bore 23a to receive the threads of bolt 24. With the construction described, the nut 18 may be locked in any one of a plurality of positions by turning it so that one of the flat sides 22 of the polygonal end is juxtaposed to the slot 25, inserting the wedge-key 21 and locking it in place with the bolt 24. As shown in the drawings, the polygonal upper end of the shank 15 is triangular, but if a finer adjustment is desired this nut may be made rectangular, hexangular or octangular.

25 When the load on the hook exceeds a predetermined value, the springs 18 and 19 compress to permit downward movement of the shank 15 out of the housing 4. It is desirable that during such separating movement a seal against dirt and other foreign matter be maintained about the shank 15 and between the lower end of the housing 4 and the upper end of the hook body 33. To this end we have provided on the lower end of the housing 4 a sleeve 13 which is adapted to ride vertically therealong in response to movement of the shank 15 and has a packing ring 13a which slides over a smooth cylindrical surface portion of the housing 4, thereby maintaining a seal with the housing regardless of vertical movement of the sleeve therealong. At its lower end the sleeve 13 is provided with a re-entrant annular wall portion 65 which in turn has an inwardly extending flange 67 thereon, the upper face of which constitutes a shoulder bearing against the underside of the edge of the flange 27 on the shank 15 so that the sleeve 13 is constrained to follow the shank downwardly when the latter moves with respect to the housing 4. When the shank 15 moves upwardly, with respect to the housing 4, the sleeve 13 is forced to follow the shank by contact with the upper end of the hook body 33, which moves vertically with the shank 15. Thus there is defined between the re-entrant wall 65 of the sleeve 13 and a downwardly depending skirt 13b on the sleeve, an annular channel in which is slidably mounted for vertical movement a ring 59, which ring is provided with a packing ring 68 sealing with the inner surface of the skirt 13b.

60 The lower end of the ring 59 is provided with a concave spherical surface 62 adapted to bear against a corresponding convex spherical surface on the upper end of the hook body 33. The ring 59 is maintained in engagement with the juxtaposed spherical surface of the hook body 33 by a plurality of helical springs 60 which are compressed between a seat 61 in the ring 59 and the upper end of the channel in the skirt 13b, in which the ring 59 is positioned. Each of the 65 springs 60 is partially enclosed in a cylindrical housing extending upwardly from the upper surface of ring 59, as clearly shown in Figs. 3a, 6 and 7.

In accordance with the invention, the hook 75 body 33 is connected to the shank 15 for unlim-

ited rotation about the vertical axis of the shank 15 and also for swivel movement in any lateral direction with respect to the axis of shank 15. To this end shank 15 is threaded at its lower end, within the hook body 33, to receive a nut 30 which is secured against accidental rotation of the shank 15 in the same manner as is the nut 18 (previously described) on the upper end of the shank. This nut 30 is provided with a concave spherical surface 32 having a center of curvature 10 the same as the center of curvature of the spherical surface on the upper end of the hook body which bears against the spherical surface 62 on the ring 59. The spherical surface 32 on the upper end of nut 30 bears against a corresponding convex spherical surface on a lower bearing race 40 of an antifriction bearing (shown in the drawings as a ball bearing), the upper race 38 of which bearing rests in an annular seat 36 formed in the body member 33. The upper race 38, 20 seated in the hook body 33, is rotatably supported on the lower race member 40, which rests against the nut 30 on the shank 15. The body member 33 is thereby rotatably supported by the bearing on the shank 15 for unlimited rotation about the 25 axis of the shank. It is also oscillatable in any vertical plane passing through the axis of the shank 15 by virtue of the sliding contact between the spherical surface on the nut 30 and the lower bearing race 40. Such oscillatory movement is 30 possible without permitting the entry of dirt into the interior of the body member 33 by virtue of the seal between the spherical surfaces on the ring 59 and the upper end of the body 33, respectively, which spherical surfaces have the same 35 center as the spherical surface 32 on nut 30. By virtue of the fact that the ring 59 is constantly pressed into intimate contact with the upper end of the hook body 33 by the spring 60, sufficient resistance is introduced to sliding movement between these surfaces to prevent the body 33 from 40 swiveling too freely about the shank 15.

It is also desirable that the frictional contact between ring 59 and the upper end of the body 33 be utilized to restrain, to a certain extent, rotation of the body 33 with respect to the housing 4. To this end it is necessary to restrain the ring 59 against rotation with respect to sleeve 13 and to restrain the sleeve 13 against rotation with respect to the housing 4. To this end the ring 59 is provided with an inwardly extending integral key 59a (Figs. 3a and 6) which extends through a slot 59b provided in the sleeve 13 and into a recess 21a provided in the flange 27 of the shank 15. The key 59a is free to move vertically 55 with respect to the sleeve 13 and the shoulder 27 but is restrained from rotation with respect thereto. Accordingly, the ring 59 is at all times constrained to rotate with the sleeve 13 and the shank 15.

To prevent any possibility of the bearing 39 leaving the seat 36 when the hook is not under load, the lower end of the sleeve 13 is shaped to define a shoulder 41 shaped to bear against the spherically curved surface on the upper end of 65 the body 33 and also form on the sleeve 13 an upwardly facing annular shoulder 42 adapted to bear against the underside of the annular flange 27 on the shaft 15. Therefore, when the nut 30 is tightened on the shank 15 into position 70 of proper adjustment, the clearance between the flange 27 and the shoulder 42 and between the shoulder 41 and the body 33 is reduced to such a small value as to prevent any appreciable separating movement between the bearing races 38 75

and 40 or between the upper bearing race 38 and its seat 36.

It is sometimes desirable to positively lock the hook body 33 against rotation with respect to the shank 15 and to this end the shank 15 has formed thereon, at a level within the upper portion of the body 33, an enlarged head 28 positioned immediately below the flange 27, which head is provided with a series of vertical slots 43 adapted to receive a locking member mounted in the body 33. Any desired number of slots 43 may be employed, but in the particular embodiment shown, four are provided. The locking member in the body 33 for cooperating with the slots 43, comprises a lever 44 mounted on a horizontal pivot pin 45 which, in turn, is rotatably mounted in a cover plate or member 46 secured to the body 33 and closing an opening leading into the hollow interior upper portion of the body in which the swivel supporting structure previously described is positioned. As shown in Fig. 5, the cover plate 46 is secured in place by bolts 51.

One end of the pin 45 (the rear end with reference to Fig. 3), extends through the cover plate 46 and has a handle 47 whereby it may be rotated. The upper end of the lever 44 extends inwardly and normally rests in one of the vertical slots 43 in the head 28 when the lever is in locked position. The lever is rotated through a small arc into locked position in which its upper end extends into one of the slots 43 or out of locked position, clear of the head 28, by means of the handle 47. In order to releasably retain the lever 44 in either locked or unlocked position, it is provided with a retractable bolt 49 slidably mounted in a longitudinal recess within the lever 44 and projecting therefrom at the upper end. The bolt 49 is constantly urged upwardly by a hollow compression spring 52 positioned in the recess in the lever 44 therebelow. The upper end of the bolt 49 is beveled on two sides to provide two faces 53 and 54, respectively, and the cover plate 46 is provided with a boss 51 on its inner surface adapted to be contacted by the bolt 49, and having a surface 55 adapted to be engaged by the surface 53 on the bolt when the lever is in locking position, and having a surface 56 adapted to be engaged by the bolt surface 54 when the lever is in unlocked position clear of the head 28. During movement of the lever 44 from either position to the other, the bolt 49 is first depressed to compress the spring 52, and is then forced outwardly again by the spring so that substantial force is required to move the lever from either extreme position to the other.

The cover plate 46 not only serves as a convenient support for the locking mechanism described, but also gives access to the interior of the body 33 and facilitates adjustment or removal of the nut 30 and the bearing, including the races 38 and 40.

As previously indicated, the hook body 33 is provided at its lower end with a bill 10 which extends forwardly and upwardly and constitutes the hook proper. When the hook is engaged with the bill, it is desirable that the hook opening be closed to prevent accidental escape of the bolt. To this end the bill 10 is slotted at its extremity, as indicated at 71, to receive a closure arm 72 which is pivotally connected to the bill by a pivot pin 73. The slot 71 in the bill is extended inwardly substantially beyond the lowermost portion of the ball-supporting surface of the bill to receive an inwardly extending finger 14 which is formed integrally with the closure arm 72 and

when the latter is in closed position the upper surface of the finger 14 is substantially flush with the ball-supporting surface of the bill.

The closure arm 72 is provided with an aperture adjacent its upper end, which aperture is adapted to receive, when the arm is in closed position, a forwardly extending lug 80 formed on the body 33. The upper wall of the aperture in arm 72 and the upper surface of the lug 80 are preferably curved about the pivot 13 as a center, so that the arm 72 is free to swing from closed to open position and have relatively small clearance with the upper surface of the lug 80 when in closed position. By providing relatively small clearance between the juxtaposed surfaces of the lug 80 and the arm 72 when the bill 10 is loaded sufficiently to cause it to yield slightly, the juxtaposed surfaces of the arm 72 and the lug 80 will be brought into contact with each other, thereby transferring part of the load to the arm 72 and the lug 80 and greatly increasing the carrying capacity of the hook.

Should the closure arm 72 not be in fully closed position at the time the load is applied to the hook, then the ball or other wedge-supporting member will contact the finger 14 on the closure arm, forcing the finger down until its upper surface is flush with the adjacent load carrying surfaces of the ball and positively forcing the closure arm 72 into closed position.

It is very desirable, of course, that when the closure arm has been once moved into closed position that it be positively locked against accidental release while at the same time being releasable by the operator. To hold the arm 72 in closed position, we provide a latch means, including a reciprocable bolt 82, mounted in the arm 72 for longitudinal motion and adapted to engage a recess 83 formed in the underside of the lug 80. The bolt 82 is supported vertically by a horizontal pivot pin 84 which is mounted in a latch carrier 85 which comprises a slotted frame slidably supported for longitudinal movement in the arm 72 and normally urged upwardly by a helical compression spring 87 positioned therebelow.

The upper end of the bolt 82 is beveled downwardly and inwardly to provide an angular end face 89 and the front underface of the lug 80 is likewise beveled downwardly and inwardly to provide an angled latch contacting face 90 so that when the arm 72 is moved from the open position toward closed position, surfaces 89 and 90 will cooperate to press the bolt 82 downwardly, allowing the arm 72 to move into fully closed position in which the aperture therein receives the lug 80, in which position the spring 87 presses the latch carrier 85 and the bolt 82 upwardly, causing the bolt 82 to move into the recess 83 and thereby lock the arm 72 in closed position.

Obviously, before the arm 72 can be opened, the bolt 82 must be retracted downwardly a sufficient distance to clear the recess 83 and such downward movement of necessity moves the latch carrier 85 downwardly against the force exerted by spring 87. In view of the fact that the axis of movement of the bolt 82 and the spring 87 is parallel to the vertical axis of the hook body, a sharp blow applied to the body 33 in the direction of its vertical axis might cause the bolt 82 to compress the spring 87 and allow the arm 72 to open accidentally. To prevent possibility of such an occurrence we provide a secondary latch comprising a T-shaped member 93, which, like the bolt 82, is pivotally mounted on the pin 84, the

member 93 being positioned in a recess in the front face of bolt 82. The member 93 has a downwardly extending leg 94, the lower end of which normally rests upon a ledge 95 on the arm 72 and thereby prevents downward movement of pin 84, and the bolt 82, with respect to arm 72. The member 93 has an upwardly extending arm 97 which bears against one end of a horizontally positioned helical compression spring 98, the opposite end of which spring is received in a recess 99 formed in the latch carrier 85. This spring constantly urges the member 93 to rotate about the pin 84 in a counter-clockwise direction (with reference to Fig. 3), thereby maintaining the lower end of the arm 94 above the ledge 95 to prevent downward movement of the bolt 82.

The member 93 is provided with a forwardly extending handle or finger 100 for manual actuation, which finger is positioned within a handle 92 on the latch carrier 85. Pressing the finger 100 on the member 93 downwardly disengages the lower end of the leg 94 from the ledge 95 to permit downward movement of the latch carrier and the bolt, and the latch carrier and bolt may then be moved downwardly by pressing downwardly on the handle 92. The upper upwardly extending arm 97 of the member 93 normally bears against the rear wall of the recess in bolt 82, in which the member 93 is partially positioned, so as to limit rotation of member 93 in counterclockwise direction in response to force exerted by the spring 98. The rear wall of the recess also acts as a stop to be contacted by the leg 94, thereby limiting rotation of the member 93 in a clockwise direction in response to movement of the downward force supplied for the finger 100.

It will be observed from Fig. 3 that the bolt 82 is not only urged into upward position into the recess 83 by spring 87, but is positively prevented from moving downwardly by the engagement of the leg 94 on member 93 with the ledge 95 on the arm 72 and the member 93 is maintained in this position by the spring 98 which is positioned with its axis of movement substantially at right angles to the axis of spring 97. Therefore should the hook receive a blow in a vertical direction capable of displacing the bolt 82 against the resilient force exerted thereon by the spring 87, the bolt would still be prevented from such movement by engagement of the leg 94 with the ledge 95 and since the latter engagement is maintained by the spring 98 positioned at substantially right angles to the spring 87, the blow that might be effective to compress spring 87 would not be effective to compress the spring 98. Likewise, should the hook receive a lateral blow in such direction as to compress the spring 98 and disengage the leg 94 from ledge 95, the bolt would not be opened because such a blow would not be effective to compress the spring 87. The bolt 82 is therefore positively prevented from opening accidentally in response to either a vertical or a horizontally applied blow, and in actual service it has been found impossible to open the bolt 82 in response to a blow applied to the hook 65 in any direction.

However, when it is desired to open arm 72, opening movement is readily effected by first depressing the finger 100 from the member 93 to disengage the leg 94 from the ledge 95 and then move the latch carrier 85, pivot pin 84 and the bolt 82 downwardly either by additional pressure applied to the finger 100 or by downward pressure applied to the handle 92 on the latch carrier.

By virtue of the fact that the finger 100 is positioned back of and slightly below the top of

the handle 92, the latter constitutes a guard for the finger 100.

The construction of the latching mechanism described is such that whereas it is necessary to manually depress the finger 100 to release the bolt 82 and permit opening movement of the arm 72, the bolt 82 will be automatically depressed in response to closing movement of the arm 72 so that the latter may be securely locked in closed position by merely slamming it shut. Thus because of the fact that the bolt 82 is pivotally attached to the latch carrier 85 by the pivot pin 84, when the arm 72 is moved into closed position, the face 89 on bolt 82 contacts the face 90 on the lug 80, the bolt 82 is rotated about the pin 84 in a clockwise direction sufficient to contact the upwardly extending arm 97 on the member 93 and rotate it against the pressure of spring 98, thereby carrying the leg 94 clear of the ledge 95. At the same time pressure between the faces 89 and 90 develops a downward component of force on the bolt 82, causing it to move downwardly (following the movement of the leg 94 clear of the ledge 95) with the latch carrier 85 against the force of the spring 87. As soon as the closing movement of the arm 72 has carried the upper end of the bolt 82 past the face 90 on the lug 80, the spring 87 urges the bolt 82 upwardly into the recess 83, and as soon as the lower end of the leg 94 moves past the ledge 95 the spring 98 rotates the member 93 to bring the lower end of the leg 94 against the ledge 95, thereby locking the bolt against downward movement until the finger 100 is manually depressed.

To limit the upward movement of the latch assembly, including the pin 84 and the elements connected thereto, a roller 104 is mounted on a horizontal pin 105 secured to the arm 72, the roller 104 being so positioned that when the latch bolt 82 is in the closed and locked position shown in Fig. 3, the roller rests upon the upper surface of the housing 99 containing the spring 98, thereby limiting upward motion of the latch carrier 85 and maintaining the spring 87 under partial compression. The force exerted by the spring 87 maintains the housing 99 against the roller 104 so that the latch mechanism cannot vibrate or rattle when in the locked position.

As shown in the drawings, particularly Figs. 1 and 2, the hook body 33, in addition to having the main bill or hook 70, is provided with a pair of oppositely disposed arms 107 positioned above the bill 70 and extending at right angles thereto for the reception and support of a pair of elevator links when the hook is employed with an elevator. To retain the elevator links on the arms 107 and at the same time support the outer ends of the arms, we provide a pair of latch arms 108 resembling in some respects the arm 72 associated with the bill 70. Thus referring to Fig. 5 each arm 108 is pivotally attached at its upper end by a pin 109 with an outwardly extending ear 110 on the body 33, the ears 110 being slotted to receive the arms 108 and permit swinging movement of the arms about the pivot pin 109. The lower end of each arm 108 is shaped to define a head 113 adapted to engage the underside of the outer end of the associated arm 107 in load carrying relation when a load is applied to the arm. Thus the juxtaposed contact faces on the shoulder 113 and the underside of the arm 107 are substantially tangential with respect to the axis of the pin 109 and there is slight spacing between the surfaces to permit free closing and opening movement of the arm 108. However, in response to a

slight downward deflection of the arm 107 when load is applied thereto, the contacting faces on the arm 107 and the latch arm 108 are brought to bear against each other and thereafter a portion of the load on the arm 107 is transferred to the latch arm 108.

To prevent any accidental opening of the arm 108 and the resultant possible escape of the elevator bails from the arms 107, each of the arms 108 is provided with a double locking device, which device also functions to retain each arm 108 in fully opened position when desired to permit ready insertion or removal of the elevator links.

This locking device comprises a lever 114 which is rotatably mounted on the pin 109 and is positioned within a recess formed in the latch arm 108. The lever 114 is provided with a rearwardly extending finger 115 and the lever 114 is constantly urged in counterclockwise direction (with reference to Fig. 5) by a torsion spring 117 to force the finger 115 against the stop lug 118 formed on the latch arm 108 when the latter is in closed position, and thereby limit counterclockwise movement of the lever 119. The lever 119 is normally prevented from rotating out of the position shown in Fig. 5 by the finger 115 on lever 114, the end of this finger being juxtaposed to the lug 122 on lever 119. With the lever 119 in the position shown, opening movement of the latch arm 108 is prevented by the fact that the forward face of the lug 123 on lever 119 abuts against a lug 125 formed on the arm 108. The abutting faces of the lug 123 and the lug 125 are substantially tangential with respect to the axis of the pin 120 so that any opening movement of the latch arm 108 applies a force from lug 125 and the lug 123 in a direction substantially normal to a radius torsion and from the pin 120. Of course a purely radial force applied to the lever 119 would not tend to move the latter in either direction but in any event rotation of the lever 119 in response to force applied thereto would be prevented either by the stop member 124 or the abutment of the lug 122 against the end of finger 115. In order to open the arm 108 it is necessary to first rotate the lever 114 sufficiently to cause the finger 115 to clear the lug 122 and then rotate the lever 119 upwardly and inwardly to move the lug 123 out of the path of the lug 125 after which the latch arm 108 may be swung outwardly and upwardly away from the arm 107.

It will be observed that the lever 114 extends from its pivotal axis in a direction substantially at right angles to the direction from which the lever 119 extends from its pivotal axis. Therefore a blow applied to the lug in such a direction as would tend to open one of the levers will not tend to open the other and disengagement of the latch lug is impossible without first releasing both levers. The latch lock described is therefore relatively immune to the effect of jars and jolts and is substantially proof against accidental release. However, when it is desired to release the latch arm 108 such release is readily effected by first pulling out the lever 114 and then pulling up on the lever 119. It is possible to effect both of these operations substantially simultaneously with the fingers of one hand. However, the levers 114 and 119 are both substantially completely enclosed within recesses in the arm 108 and the ear 110, respectively, so that there is little possibility of the levers being

engaged and actuated accidentally by contact with some external object.

Initial opening movement of the latch arm 108 following the release of the levers 114 and 119 as described, carries the upper face of the lug 125 past the outer face 123a of lug 123, whereupon the lever 119 may be released so that it presses against the outer curved surface of the lug 125 as the arm 108 is swung open. Final opening movement of the arm 108 carries the lug 125 past the lug 123, whereupon the lever 119 is snapped back into the normal position by the spring 126 with the face 123 on lug 123 bearing against the outer end 129 of the lug 125, thereby retaining the arm in open position until it is released by raising the lever 119 against the force exerted by the spring 126. The hook described operates as follows:

Assume that the parts are in the normal position shown in Figs. 1, 2 and 3, that the hook is suspended on a traveling block or other hoisting device connected to the bail 1, and that it is desired to support a load from the hook by means of a bail engaged with the main bill or hook 10 of the device. The latch arm 72 is first opened by bearing down on the finger 100 of the lever 93 to carry the lower end of the leg 84 clear of the ledge 86 on the latch arm 72, whereupon further downward pressure is applied either to the finger 100 or the handle 92 to carry the bolt 82 downwardly against the force exerted by spring 81, whereupon the arm 72 may be swung outwardly and downwardly to provide an opening for insertion of the bail to be suspended from the bill 70. The bail is then inserted and the arm 72 closed by slamming it shut. As the arm moves into closed position, the bevel face 89 on the end of bolt 82 strikes the face 90 on the body 83 causing the bolt 82 to rotate slightly in a clockwise direction about the pin 84 sufficiently to contact the upwardly extending arm 87 on the member 83 and rotate the latter against the force exerted by the spring 88 sufficient to carry the leg 84 clear of the ledge 85, whereupon the downward component of force supplied to the bolt 82 by contact of the face 89 thereon with the face 90 on the body 83, moves the bolt down to clear the body member and permit it to pass into the recess 83, the latch arm 72 at the same time moving into fully closed position, whereupon it is locked in that position by movement of the bolt 82 into the recess 83 under the force exerted by the spring 81.

Should for any reason the latch arm 72 not be fully closed, then when the hook is elevated to apply lifting force to the bail engaged thereby, the bail will bear against the finger 14 on the latch arm 72 and complete the final rotation of the arm 72 to carry it into fully closed position. With the latch arm 72 in fully closed position, the latch bar 78 is positioned above the lug 80 on the body 83 with very slight clearance between the juxtaposed surfaces. As soon as appreciable load is applied to the bill 70, the latter deflects slightly to bring the juxtaposed surfaces of the latch bar 78 and the lug 80 together, whereupon a portion of the load on the bill is transferred to the lug 80 and the supporting strength of the bill thereby increased.

If sufficient lifting force is applied through the hook structure to the load suspended on the bill 70, the springs 18 and 19 will be further compressed, permitting the shank 15 and the parts connected thereto to move downwardly with respect to the housing 4 until the lower edge of

the nut 16 on the upper end of shank 15 rests against a shoulder 9 (Fig. 3) in the housing 4. During this downward movement the sleeve 13 is carried downwardly with the shank 15 by engagement of the flange 27 on the shank with the flange 42 on the sleeve. However, a seal is still maintained between the sleeve 13 and the housing 4 by virtue of the packing ring 13a, so that entry of dirt into the housing 4 is at all times prevented.

During the application of forces insufficient to fully compress the springs 18 and 19, lifting force is applied from the ball 1 to the upper end of the housing 4 and thence through the entire length of the housing 4 to the flanges 20 and 21 which bear against the lower ends of the springs 18 and 19. However, when the lifting force is increased beyond the strength of the springs 18 and 19, the nut 16 comes to rest against the shoulder 9 and all additional lifting force over that required to compress the springs 18 and 19 is applied from the ball 1 only through the upper portion of the housing 4 situated above the shoulder 9 therein. Therefore the lifting force applied through the portion of the housing 4 positioned below the shoulder 9 is definitely limited, and this lower portion of the housing can be made relatively light and thin, it being only necessary to make the upper portion of the housing, down through and including the shoulder portion 9, sufficiently strong and heavy to withstand the maximum lifting forces to which the hook may be exposed in use.

If for any reason the load supported by the hook is not directed exactly along the axis of the hook, the body 33 is free to swivel in any horizontal direction with reference to the shank 15 to prevent bending strains being applied to the hook, the swiveling movement taking place along the spherical contact surfaces of the bearing rest member 40 and the supporting nut 32 on the lower end of shank 15. If desired, free oscillation between the body 33 and the housing 4 is prevented by friction of the ring 59 against the bearing nut of body 33, contact between these parts further preventing entry of dirt into the interior of the device.

If it is desired to prevent free rotation of the load supported by the hook, the handle 41 is actuated to rotate the lever 44 into the position shown in Fig. 3, in which the inner end of the lever engages one of the slots 43, thereby preventing rotation of the body 33 relative to the shank 15. On the other hand, if it is desired to permit free rotation of the load, the handle 41 is actuated to rotate the lever 44 in the opposite direction to carry the inner end of the lever clear of the head 28 and the slot 43 therein. The lever 44 is retained in either position to which it may be moved by friction between the bolt 49 and the cam surfaces 55 and 56. When the lever 44 is disengaged from the slots 43, the body 33 is free to rotate with respect to the shank 15; hence its only contact therewith is through the bearing member comprising the races 39 and 40 and the smooth surfaces on the upper end of the body 33 and the lower face of the ring 59, respectively.

When it is desired to employ the hook with an elevator having two balls, the latter may engage with the arms 107 by first pulling out on the lever 114 and upwardly on the lever 119 to release the arms 108 and then swinging the latter outwardly in substantially horizontal position in which they will be automatically retained by lugs 123 on the levers 119 and the lugs 125 on the arms 108. The

elevator balls are then placed in position on the arms 107 and the arms 108 closed by lifting the levers 119 to disengage the lugs 123 from the lugs 125 and moving the arms 108 into closed position in which they are locked by engagement of the lugs 123 on the levers 119 with the lugs 125 on the arms 108 and by the positioning of the fingers 116 on levers 114 in juxtaposed relation to the lugs 122 on levers 119.

Although the invention has been explained by describing in detail a particular structure in accordance therewith, it is to be understood that various modifications can be made in the particular structure shown without departing from the invention, and the latter is to be limited only as set forth in the appended claims.

We claim:

1. A hook structure comprising a hook member for engaging a load, a supporting member for supporting said hook member, a pair of bearing elements having complementary spherical contact surfaces relatively slidable on each other, means connecting one of said bearing elements to said supporting member, and means connecting the other of said bearing elements to said hook member, in which at least one of said connecting means comprises antifriction bearing means rotatably interconnecting the bearing element and member associated therewith.

2. A hook structure comprising a hook member for engaging a load, a supporting member for supporting said hook member, and means interconnecting said members for relative swinging movement comprising a stem on one of said members, and a head on said stem having a spherical bearing surface, an annular element on said other member bearing against said first-mentioned spherical surface, and thereby preventing separating movement of said two members while permitting relative oscillation therebetween in any direction, in which said annular element comprises a pair of bearing members relatively rotatable with respect to each other about the axis of said annular element whereby said hook member can rotate relative to said supporting member about the axis of said annular element, independently of movement along said spherical surface.

3. A hook structure comprising a hook member for engaging a load, a supporting member for supporting said hook member, and means interconnecting said members for relative swinging movement in any direction, comprising a stem on one of said members and a head on said stem having a concave spherical bearing surface thereon, an annular element on said other member having a convex spherical surface bearing against said concave spherical surface on said head and thereby preventing separating movement of said two members while permitting relative oscillation in any direction.

4. A hook structure as described in claim 3, in which said annular element has a second convex spherical bearing surface on the opposite side thereof from said first mentioned spherical surface, said second surface having the same swinging center as said first surface, and means connected to said stem and juxtaposed to said second convex surface for limiting separating movement of said first mentioned spherical annular member and head.

5. A hook structure as described in claim 3, in which said annular element has a second convex spherical bearing surface on the opposite side thereof from said first mentioned spherical sur-

face, said second surface having the same center of curvature as the first-mentioned surface, and resilient friction means connected to said stem and bearing against said second mentioned spherical surface on said annular member for damping movement between said two members.

6. A hook structure comprising a hook member for engaging a load, a supporting member for supporting said hook member, and means interconnecting said members for relative swinging movement in any direction comprising a stem on one of said members, a head on said stem having a spherical bearing surface, an annular element on said other member bearing against said spherical surface and thereby preventing separating movement of said two members while permitting relative oscillation therebetween in any direction and in which said annular element comprises two members, bearing means of the 20 rolling contact type interconnecting said members for relative rotation about the axis of said annular element, a second spherical surface on said annular element opposite said first spherical surface thereon, and having the same center of 25 curvature, and means connected to said stem for resiliently contacting said last-mentioned spherical surface and frictionally resisting rotation of said hook member relative to said supporting member.

30 7. A hook structure comprising a hook member for engaging a load, and a supporting member for supporting said hook member with means interconnecting said members for relative swinging movement in any direction comprising a 35 stem on said supporting member, a head on said stem having a spherical bearing surface thereon, said hook member comprising a hollow body receiving said stem and head and having an opening in the upper end through which said stem 40 extends, and means connected to said stem for engaging and sealing with the outer surface of said body all the way around said opening in all relative positions of said supporting member and said hook member, said body member including 45 an annular member having a spherical surface engaging said spherical surface on said head for supporting said body on said stem for swinging movement relative thereto.

8. A hook structure as described in claim 7 50 in which the outer surface of said body adjacent said opening therein is spherical about the same center of curvature as said first mentioned spherical surface, and means connected to said stem and juxtaposed to said last mentioned spherical bearing surface on said body for limiting separating movement of said first mentioned spherical surfaces.

9. A hook structure comprising a hook member for engaging a load, a supporting member 60 for supporting said hook member, and means interconnecting said members for swivel movement therebetween comprising a stem on said supporting member, a head on said stem, means on said hook member engaging said head, where- 65 by said hook member is suspended from said stem, said stem having a vertical recess therein, a bolt, and means mounting said bolt on said hook member for substantial radial movement into and out of engagement with said recess in 70 said stem to lock and unlock said member with respect to relative swiveling motion therebetween.

10. A device as described in claim 9, in which 75 said bolt comprises an arm on a shaft, means for supporting said shaft for rotation, and a handle exterior of said hook member and connected to

said shaft for rotating the latter into and out of engagement with said recess in said stem.

11. A hook structure as described in claim 9, in which said bolt comprises a shaft rotatably mounted in said hook member with an arm on 5 said shaft having a portion extending substantially radially from said shaft and an end portion extending angularly from said first mentioned portion for engaging said recess in said stem with a spring detent in the end of said first mentioned radial portion of said arm, and cam means on said hook member adapted to depress said detent during movement of said arm from position in engagement with said recess to position clear of said recess for frictionally retaining said arm in whichever position it has been moved.

12. A hook structure as described in claim 9, in which said hook member comprises a hollow housing containing said recessed stem, said 20 housing having an aperture therein with a detachable cover plate secured to said housing over said aperture, and means for supporting said bolt on said cover plate.

13. A hook structure comprising a hook member having an upwardly extending stem thereon, a head on said stem adjacent the upper end thereof, a supporting member for supporting said hook member comprising a housing surrounding said stem and slidably vertically therealong, 25 means for applying a lifting force to the upper end of said housing, spring means interconnecting the lower end of said housing and said head on said stem for transferring small lifting forces 30 applied to said housing from said stem, said spring means yielding in response to heavy forces 35 to permit sliding movement of the housing downwardly along the stem, and means for limiting such movement and applying lifting force from said housing directly to said stem, comprising 40 shoulder means on said stem and cooperating shoulder means adjacent the upper end of said housing adapted to abut against said shoulder means on said stem, whereby the portion of the 45 housing below said shoulder means thereon is subjected only to the small lifting forces applied to said hook member through said spring.

14. A hook structure as described in claim 13 50 with swivel means interconnecting said stem to said hook member for unyieldably supporting said hook member with respect to said stem, while permitting rotary and swinging movement of the latter.

15. A hook structure as described in claim 13, with a sleeve slidable on the lower portion of 55 said housing and sealing therewith, means fixing said sleeve with respect to said stem for vertical movement therewith, and means for effecting a seal between the lower end of said sleeve and said hook member.

16. A hook structure as described in claim 13, in which said hook member comprises a hollow housing, swivel means within said housing interconnecting said stem to said hook member for permitting rotary and swinging movement of the 65 hook member with respect to said stem, a sleeve slidably on the lower portion of said first mentioned housing and sealing therewith, means fixing said sleeve with respect to said stem for vertical movement therewith, and means for effecting a seal between the lower end of said sleeve and said second mentioned housing on 70 said hook member, whereby both said housings are retained in sealed condition irrespective of 75

relative movement between said stem and said housing.

17. A hook structure comprising a hook member for engaging a load, a supporting member for supporting said hook member, a stem on one of said members, bearing means on said stem, and an annular element on the other of said members having aspherical bearing surface bearing against said bearing means on said stem for supporting said hook member for swinging movement but against separating movement with respect to said supporting member, in which said annular element has a second spherical bearing surface having the same center of curvature as the first-mentioned spherical surface thereon and said stem has means connected thereto for resiliently contacting said second spherical surface on said annular element and frictionally resisting rotation of said hook member relative to said supporting member.
18. A hook structure comprising a hook member for engaging a load, a supporting member for supporting said hook member, a stem on one of said members, bearing means on said stem, and

an annular element on the other of said members having a spherical bearing surface bearing against said bearing means on said stem for supporting said hook member for swinging movement but against separating movement with respect to said supporting member, in which said annular element has a second spherical bearing surface having the same center of curvature as the first-mentioned spherical surface thereon and said stem has means connected thereto for resiliently contacting said second spherical surface on said annular element and frictionally resisting rotation of said hook member relative to said supporting member.

19. A hook structure comprising a hook member for engaging a load, a supporting member for supporting said hook member and including a housing, a coil compression spring mounted in said housing, a stem slidably and yieldably supported by said spring and extending through the lower end of said housing, and connecting means comprising a ball and socket connection between said hook member and said stem.

relative movement between said stem and said housing.

17. A hook structure comprising a hook member for engaging a load, a supporting member for supporting said hook member, a stem on one of said members, bearing means on said stem, and an annular element on the other of said members having as spherical bearing surface bearing against said bearing means on said stem for supporting said hook member for swinging movement but against separating movement with respect to said supporting member, in which said annular element has a second spherical bearing surface having the same center of curvature as the first-mentioned spherical surface thereon and said stem has means connected thereto for resiliently contacting said second spherical surface on said annular element and frictionally resisting rotation of said hook member relative to said supporting member.
18. A hook structure comprising a hook member for engaging a load, a supporting member for supporting said hook member, a stem on one of said members, bearing means on said stem, and

an annular element on the other of said members having a spherical bearing surface bearing against said bearing means on said stem for supporting said hook member for swinging movement but against separating movement with respect to said supporting member, in which said annular element has a second spherical bearing surface having the same center of curvature as the first-mentioned spherical surface thereon and said stem has means connected thereto for resiliently contacting said second spherical surface on said annular element and frictionally resisting rotation of said hook member relative to said supporting member.

19. A hook structure comprising a hook member for engaging a load, a supporting member for supporting said hook member and including a housing, a coil compression spring mounted in said housing, a stem slidably and yieldably supported by said spring and extending through the lower end of said housing, and connecting means comprising a ball and socket connection between said hook member and said stem.
